DESIGN FOR A STORE FRONT

Mortimer Levitt, New York, N. Y.

Application November 18, 1937, Serial No. 72,982

Term of patent 14 years

To all whom it may concern:

Be it known that I, Mortimer Levitt, a citizen of the United States, residing at 91 Charles Street, New York, N. Y., have invented a new, original, and ornamental Design for Store Front, of which the following is a specification, reference being had to the accompanying drawing forming part thereof.

Fig. 1 is a front elevational view of a store front embodying my new design; and

Fig. 2 is a view of the store front taken on the line 2—2 of Fig. 1.

The drawing is lined to indicate contrasting colors.

I claim:

The ornamental design for a store front substantially as shown and described.

MORTIMER LEVITT.
